DEVICE FOR AUTOMATICALLY ROTATING
CASES OF BOTTLED FLUID

Richard C. Wilson, Des Moines, Iowa

Application November 27, 1939, Serial No. 306,302

3 Claims. (Cl. 259—57)

The principal object of my invention is to provide a device that will automatically turn and rotate cases of bottles holding mixtures of fluids, such as certain beverages, whereby the turning and rotating of the case will successfully mix the ingredients in each of the bottles in the case.

A further object of this invention is to provide a case rotating device that will rotate the case a predetermined number of rotations end over end, but will securely and safely hold the case during the rotation period.

A still further object of this invention is to provide a device for rotating cases that will be quickly and easily adjusted to fit cases of different types and different sizes.

A still further object of this invention is to provide an automatic case rotating device that is easily manipulated and one that is under the complete control of the operator at all times.

20 A still further object of this invention is to provide a case rotator that is capable of automatic operation by the mere feeding of the cases to and into the same.

A still further object of this invention is to 25 provide a device for turning and rotating cases of bottled beverages and like that is economical in manufacture and durable in use.

These and other objects will be apparent to those skilled in the art.

30 My invention consists in the construction, arrangement and combination of the various parts of the device, whereby the objects contemplated are attained as hereinafter more fully set forth, pointed out in my claims and illustrated in the 35 accompanying drawings, in which:

Fig. 1 is a side view of my device ready for use.

Fig. 2 is a top plan view of my device for automatically rotating cases of bottled beverage or like.

40 Fig. 3 is a top plan view of my apparatus with upper portions cut away to more fully illustrate its construction.

Fig. 4 is an enlarged end sectional view of a portion of my device.

45 Fig. 5 is an enlarged side view of the timing cam used in the device.

Fig. 6 is an enlarged side view of the cam roller assembly.

50 Fig. 7 is an enlarged bottom plan view of a portion of the device.

Fig. 8 is a side cross sectional view of the portion of the device illustrated in Fig. 7.

55 Fig. 9 is an enlarged side view of the automatic starting mechanism of the device.

Fig. 10 is an enlarged side view of the roller switch and its operating finger.

It is common practice in any bottling works to tumble the bottles end over end after they have been capped in order to properly mix the ingredients inside the bottle. This is particularly true of many kinds of bottled beverages. The usual practice is to use automatic machinery that will individually pick up each bottle and tumble it automatically. Such machinery, however, is very slow, costly and complicated and much breakage of the bottles is experienced. I have overcome such objections by providing an apparatus that will tumble and rotate automatically an entire case of bottled goods.

15 Referring to the drawings, I have used the numeral 10 to designate the table of my device. The numeral 11 designates a top portion of the table on the upper right hand portion of the table frame. This flat surface portion 11 extends 20 upwardly and inwardly toward the center portion of the table. The numeral 12 designates the second top section of the table and which is located on the upper left hand corner portion. This flat table top portion 12 extends upwardly 25 and inwardly toward the center portion of the table and is spaced apart from the top portion 11 to provide a substantial space between the members 11 and 12, which I have designated by the numeral 13. The numeral 14 designates rows of 30 ordinary rollers rotatably mounted in and on the table top portions 11 and 12, as shown in Fig. 2. These rollers extend longitudinally of the table and their upper portions reach planes above the table top portions to which they are secured in 35 order to support and facilitate the manual sliding of boxes, crates or like across the table.

The numerals 15 and 16 designate two bearing members on the table frame 10 extending vertically above the table. These two spaced apart 40 bearing members are positioned substantially equal distances between the table top portions 11 and 12. The numeral 17 designates a stub shaft rotatably mounted in the bearing 15. The numeral 18 designates a stub shaft rotatably 45 mounted in the bar 16. These two stub shafts 17 and 18 have their inner ends suitably secured to the two outer sides respectively of an open ended trough member 19. This trough member 19 is positioned between the two sections 11 and 50 12 as shown in Fig. 2, and the bottom of the trough when the same is in a horizontal position is substantially flush with the inner ends of the sections 11 and 12. Due to the slopes of the sections 11 and 12, the inner edge of the member 11 55

is usually slightly above the inside bottom of the trough 19, while the inner end of the section 12 may be slightly below the inside bottom of the trough 19, in order that crates or cases may be 5 easily slid from the portion 11 into the trough portion and from the trough portion onto the section 12.

The numeral 20 designates an inverted open ended trough portion telescoping with the portion 19, as shown in Fig. 4. By this arrangement the distance between the bottoms of the members 19 and 20 may be adjustably held. The members 19 and 20 may be rigidly secured together after the proper adjustment has been obtained by any 15 suitable means such as screws 21 extending through slots 22 in the sides of the member 19 and threaded into the sides of the member 20. These two members 19 and 20 form a box member open at its two ends and is designed to hold 20 the case of bottled fluid during the tumbling process.

Obviously when the shaft 18 is rotated, this box housing will rotate end over end. The numeral 23 designates an electric motor on the table 10. 25 The numerals 24 and 25 designate two electric lead lines, each having one of their ends connected to the motor 23 in the usual manner and their other ends designed to be in communication with the negative and positive sides of a 30 suitable source of electrical energy. The numeral 26 designates an ordinary switch of the compressible roller type embodied in the electric circuit of the two lead wires 24 and 25. This switch is secured to the frame of the table 10 35 and below the section 12. The numeral 27 designates the compressible roller of this circuit-breaking switch. The numeral 28 designates a sprocket wheel operatively connected to the motor 23. The numeral 29 designates a shaft suitably rotatably mounted to the lower frame portion of the table 10. The numeral 30 designates a friction clutch of the ordinary type embracing the shaft 29 and connected to the sprocket wheel 31. The numeral 32 designates an endless chain embracing the sprocket wheels 28 and 31. The numeral 33 designates a sprocket wheel on the shaft 18. The numeral 34 designates a sprocket wheel on the shaft 29. The numeral 35 designates an endless chain embracing the sprocket 40 wheels 33 and 34. By this arrangement when the motor is running, the shaft 29 will yieldingly rotate, thereby rotating the shaft 18 which will rotate the case or crate housing and shaft 17. The numeral 36 designates a plate member slidably mounted on the table frame 10 and just below the inner end portion of the member 12. This member 36 is capable of sliding to a position under the left end portion of the member 19 and is depressed near its center portion as 45 shown in Fig. 4, to permit the clearance at times of certain parts yet to be explained. The numeral 37 designates a shaft operatively slidably mounted to and longitudinally of the member 10, having one end capable of engaging the member 36, as shown in Fig. 3. The numeral 38 50 designates a shaft rotatably mounted on the member 10 and below the section 11. This shaft 38 extends transversely of the table and has a finger 39 secured to its center. This finger 39 is capable of extending upwardly above the section 11 through a slot 40 in the section 11, as 55 shown in Fig. 1. This slot 40 is positioned longitudinally of the section 11, near its inner end, and between the two rows of rollers 14 on the section 11. When the finger 39 extends above the sur-

face of the top 11, it extends upwardly and inwardly toward the center portion of the table. The numeral 41 designates a movable catch on the upper surface of the member 11 for locking the finger 39 in a lowered condition at times. 5 The numeral 42 designates an arm having one end rigidly secured to the shaft 38. The numeral 43 designates a link having one end pivoted to the shaft 37 and its other end pivoted to the lower end of the arm 42, as shown in Fig. 9. 10 By this arrangement when the finger 39 is depressed, the shaft 37 will be moved out of engagement with the member 36 and when the finger is in an elevated position, the shaft 37 will be in a forward sliding position. When the 15 shaft 37 is in such forward position, it will have moved the plate 36 forwardly to the left and out from under the forward end of the member 19.

The numeral 44 designates a coil spring having one end operatively engaging the table 10 20 and its other end engaging the shaft 37 for yieldingly holding the finger 39 in an elevated condition. The numeral 45 designates a sprocket wheel secured to a cam 46, which in turn is suitably operatively mounted to the frame of the 25 member 10. The numeral 47 designates a sprocket wheel on the shaft 17. The numeral 48 designates an endless chain embracing the sprocket wheels 45 and 47. The numeral 49 designates an idler wheel engaging the chain 38. The numeral 50 designates an arm secured to the member 36. The numeral 51 designates a roller mounted on the free end of the arm 50 and capable of engaging and rolling on the periphery of the cam 46. The numeral 52 designates a 30 second arm secured to the member 36 and capable of engaging and depressing the switch roller 27 when the member 36 is slid forwardly and to the left. By this construction, when the member 36 is moved forwardly and to the left, the switch 40 roller 27 will be depressed and the electric circuit will be completed by the switch, thereby causing the motor 23 to operate. The numeral 53 designates a coil spring having one end operatively connected to the member 36, and its 45 other end operatively connected to the table for yieldingly holding the member 36 toward and under the forward end of the member 19.

The numeral 54 designates a plurality of holes in the center rear bottom portion of the member 19. The numeral 55 designates a leaf spring adjustably positioned on the bottom of the member 19 by a bolt, screw or like 56. The numeral 57 designates a lug catch element on the free end of the member 55 capable of extending 55 through one of the holes 54. This member 57 has its upper end extending inwardly and upwardly as shown in Fig. 8. By this construction a case may be slid into the housing and over this catch 57, but after it has passed the member 57, the member 57 will move upwardly and prevent the removal of the case from the housing in the same direction from whence it came.

By adjusting the member 55 on the bottom of the member 19, different sized cases may be handled in my device.

The numeral 58 designates a shaft rotatably mounted on the bottom of the member 19. This shaft 58 extends longitudinally of the member 19 and has its forward end capable of extending 70 above the member 36 when the member 36 is in a rearward position. The numeral 59 designates a row of holes in the bottom center forward end portion of the member 19. The numeral 60 designates a finger slidably adjustably mounted on 75

the shaft 58 and capable of extending upwardly through one of the holes 59 when the shaft 58 is rotated. The finger 60 may be adjustably positioned along the length of the shaft 58 so that it will enter any one of the desired holes 59. Obviously the distance between the member 60 and member 57 would be only slightly greater than the length of the case to be tumbled. The numeral 61 designates an arm on the shaft 58 capable of engaging the plate 36 when the plate 36 is in a rearward position. By this arrangement when the plate 36 is in a rearward position, the member 61 will engage it, thereby rotating the shaft 58 and moving the finger 60 below the upper surface of the member 19. The numeral 62 designates a coil spring for yieldingly holding the arm 61 in a lowered condition when the same is not engaged by the bar 36. When the bar 36 is in a forward position, the member 61 will move downwardly, thereby bringing the finger 60 to a position above the surface of the member 19. I have used the numeral 63 to designate a crate, box, case or like. To facilitate the movement of cases into and out of the member 19, I have provided ordinary supporting rollers 64 in the bottom of the member 19.

The practical operation of my device is as follows:

With a case resting on the member 11 and ready to be tumbled, the finger 39 will be depressed, the bar 36 will be in a rearward position, the roller 51 will be in the groove of the cam 46, the switch 26 will be open and the case holding housing comprising the members 19 and 20 will be in a position as shown in Fig. 1. It is merely necessary to push the case to be tumbled forwardly over the catch 57 and into the members 19 and 20, which make up the housing. The case will move forwardly until it engages the member 60, which will prevent its further movement through the member 19. The catch lock 57 will move upwardly to the rear of the case and prevent its removal in that direction. Immediately upon the passing of the case from the finger 39, the spring 44 will raise the finger 39 and move the shaft 37 forwardly, thereby forcing the bar 36 forwardly and to the left. This action of the movement of the member 36 forwardly will be prior to the case reaching the forward end of the member 19 and, therefore, as herebefore explained, the member 60 will be in an elevated condition to prevent the complete sliding of the case through the housing. With the member 36 moved forwardly, the arm 52 will depress the switch roller and start the prime mover 23. Also with the member 36 in a forward position, the roller 51 will be moved free of the cam 46. With the motor rotating, the housing 19 and 20 will start to rotate end over end, carrying with it the case of bottled goods. During this operation, another case is moved into position on the member 11, which depresses the finger 39. With the finger 39 held downwardly, the shaft 37 will be slid to the right and out of engagement with the member 36. The member 36, however, cannot move rearwardly immediately, inasmuch as the roller 51 will be engaging the major portion of the circumference of the cam 46. However, with the housing rotating, the shaft 17 will rotate, which will cause the cam 46 to rotate also. Eventually the depression in the cam 46 will move adjacent the roller 51 and when this takes place, the roller will enter the groove of the cam, thereby permitting the spring 53 to move the arm 50 and member 36 rearwardly. The arrangement, position and timing of all of the parts are such that the normal rear end of the housing will not engage the bar 36 but the next time the housing approaches a normal horizontal position, as shown in Fig. 1, the arm 61 will engage the bar 36, thereby lowering the holding finger 60. Usually the slope will be such that the case inside the housing, will by force of gravity roll out onto the members 14 on the table top 12. Of course, the motor will be shut off at a period of time slightly before the housing reaches this position for the simple reason that when the member 36 moves to the rear at the time when the roller 51 enters the groove of the cam, the arm 52 will move out of engagement with the roller 27, breaking the electric circuit. Although the timing is such that the motor will cut off shortly before the housing reaches a normal horizontal position, the momentum of rotation of the housing will be sufficient to carry it to a point where the member 61 engages the bar 36. Obviously the device can be so constructed as to provide any number of rotations of the housing before the cam 46 reaches a position to permit the movement of the bar 36 to the rear. From the foregoing it will readily be seen that my device will automatically rotate entire cases of bottled fluids. If it is desired to not have the device automatically stopped after a predetermined number of rotations, it is merely necessary to permit the cam 39 to be in an elevated position and the spring 44 will continue to hold the bar 36 forwardly and the housing will continue to rotate. If no second case is available and it is desired to stop the rotating of the housing, the finger 39 may be depressed and the catch member 41 swung over it in order to hold it in a lowered condition. The housing may be held against rotation at any time by merely manually grasping it. The clutch 30 provides this desirable and safety feature.

Some changes may be made in the construction and arrangement of my improved device for automatically rotating cases of bottled fluid, without departing from the real spirit and purpose of my invention, and it is my intention to cover by my claims any modified forms of structure or use of mechanical equivalents which may be reasonably included within their scope.

I claim:

1. In a device of the class described, a table having an opening in its top, a housing open at both its ends rotatably mounted in said opening, a means for rotating said housing at times, a bar member slidably mounted on the forward end portion of said table and capable of rearward sliding movement to a position under one end of said housing, and a depressible finger on the rear portion of said table operatively connected to said bar and capable of moving said bar rearwardly of said housing when depressed; said finger positioned at the rear of said housing and designed to be held in a depressed position by a case of bottled fluid at times, a catch means on one end portion of said housing, and a latch means on the other end portion of said housing capable of engagement with said bar when said bar is in a position under said housing; said latch means being rendered inoperative by said engagement with said bar.
2. In a device of the class described, a table having an opening in its top, a housing open at both its ends rotatably mounted in said opening, a means for rotating said housing at times, a

bar member slidably mounted on the forward end portion of said table and capable of rearward sliding movement to a position under one end of said housing, and a depressible finger on the 5 rear portion of said table operatively connected to said bar and capable of moving said bar rearwardly of said housing when depressed; said finger positioned at the rear of said housing and designed to be held in a depressed position by a 10 case of bottled fluid at times, a spring means for yieldingly holding said bar in a position under one end of said housing at times, and a cam means operatively connected to said housing and to said bar for preventing the movement of said 15 bar to a position under one end of said housing until said housing has rotated a predetermined number of revolutions.

3. In a device of the class described, a table having an opening in its top, a housing open at 20 both its ends rotatably mounted in said opening, a means for rotating said housing at times, a bar member slidably mounted on the forward end portion of said table and capable of rearward

sliding movement to a position under one end of said housing, and a depressible finger on the rear portion of said table operatively connected to said bar and capable of moving said bar rearwardly of said housing when depressed; said finger positioned at the rear of said housing and designed to be held in a depressed position by a case of bottled fluid at times, a spring means for yieldingly holding said bar in a position under one end of said housing at times, a cam means 10 operatively connected to said housing and to said bar for preventing the movement of said bar to a position under one end of said housing until said housing has rotated a predetermined number of revolutions, an electric motor operatively 15 connected to said housing, an electric circuit connected to said motor and designed to be in communication with a source of electrical energy, and a switch imposed in said circuit and capable of being operatively actuated by the movement 20 of said bar.

RICHARD C. WILSON.
